(57) **CLAIM**

The ornamental design for a protector for medical device, as shown and described.

DESCRIPTION

FIG. 1 is a perspective view of a protector for medical device;
FIG. 2 is a front view thereof;
FIG. 3 is a rear view thereof;
FIG. 4 is a right-side view thereof;
FIG. 5 is a left-side view thereof;
FIG. 6 is a top view thereof; and,
FIG. 7 is a bottom view thereof.

The broken lines depict environmental subject matter only
and form no part of the claimed design.
